US00D938585S

(12) **United States Design Patent** (10) **Patent No.:** **US D938,585 S**
(45) **Date of Patent:** **** Dec. 14, 2021**

(54) **IMPLANT DELIVERY APPARATUS**(71) Applicant: **GLAUKOS CORPORATION**, San Clemente, CA (US)(72) Inventors: **Charles Raymond Kalina, Jr.**, Irvine, CA (US); **James Robert Dennewill**, Anaheim, CA (US)(73) Assignee: **Glaukos Corporation**, San Clemente, CA (US)(**) Term: **15 Years**(21) Appl. No.: **29/757,235**(22) Filed: **Nov. 4, 2020****Related U.S. Application Data**

(62) Division of application No. 29/682,793, filed on Mar. 7, 2019, now Pat. No. Des. 901,683, which is a division of application No. 29/623,940, filed on Oct. 27, 2017, now Pat. No. Des. 846,738.

Primary Examiner — Wan Laymon(74) *Attorney, Agent, or Firm* — Knobbe, Martens, Olson & Bear, LLP(57) **CLAIM**

The ornamental design for an implant delivery apparatus, as shown and described.

DESCRIPTION

FIG. 1 is a front, top, and left side perspective view of an implant delivery apparatus showing our design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

All features illustrated in broken lines form no part of the claimed design.
